UNITED STATES PATENT OFFICE.

JAMES H. SPENCER, OF NEW YORK, N. Y., ASSIGNOR TO SPENCER & CO., OF SAME PLACE.

TELEPHONE-TRANSMITTER.

SPECIFICATION forming part of Letters Patent No. 624,697, dated May 9, 1899.

Application filed March 31, 1898. Serial No. 675,892. (No model.)

To all whom it may concern:

Be it known that I, JAMES H. SPENCER, of the city of New York, borough of Manhattan, in the county and State of New York, have invented a new and Improved Telephone-Transmitter, of which the following is a full, clear, and exact description.

The object of the invention is to provide a new and improved telephone-transmitter which is simple and durable in construction, not liable to get out of order, and which is sufficiently sensitive for ordinary purposes.

The invention consists of novel features and parts and combinations of the same, as will be described hereinafter and then pointed out in the claims.

Reference is to be had to the accompanying drawings, forming a part of this specification, in which similar characters of reference indicate corresponding parts in all the figures.

Figure 1 is a rear face view of the improvement. Fig. 2 is a transverse section of the same on the line 2 2 of Fig. 1, and Fig. 3 is an inverted sectional plan view of the same on the line 3 3 of Fig. 1.

The improved telephone-transmitter is provided with a ring-shaped frame A, formed with an annular seat A' for the disk B, made of rubber or like material and of considerable thickness, so as to be rendered but slightly flexible in contradistinction to the thin extremely flexible diaphragms ordinarily employed in telephone-transmitters. The disk B is preferably dished somewhat on both faces, as shown in Figs. 2 and 3. The disk B is firmly held to its seat A by clamps C, preferably two in number, located diametrically opposite each other and secured to the frame A, each clamp extending over the back of the disk B to engage with its end C' the rear face of the disk to securely hold the same in position against the seat.

The buttons D D' of the telephone-transmitter are preferably of the construction shown and described in the Letters Patent of the United States No. 596,834, granted to J. H. Spencer and M. S. Keyes on January 4, 1898, one button D being carried by the disk B, while the other button D' is carried by a

bridge E, secured at its ends to the frame A, 50 as plainly indicated in the drawings. Electric wires F F' are connected in the usual manner one with the button D and the other to the bridge E, as shown in Fig. 1.

By securely holding the heavy disk B to its seat on the frame A and by rigidly connecting one of the buttons with the said disk sufficient vibration is given to the buttons when sounds pass upon the face of the disk to readily transmit articulate speech and 60 other sounds to a receiver of the usual construction. By having the transmitter formed with a heavy disk, as described, a considerably long life is given to the instrument, and the latter is not liable to get out of order and can 65 readily stand rough usage.

Having thus fully described my invention, I claim as new and desire to secure by Letters Patent—

1. A telephone-transmitter, comprising a 70 frame having an annular seat, a disk or diaphragm slightly dished on both faces, and resting on said seat, said disk or diaphragm being of considerable thickness so as to be but slightly flexible, clamps secured to the 75 frame and curved to bear at two points only on the disk or diaphragm, and buttons, one of which is carried by the disk or diaphragm and the other is supported from the frame, substantially as described. 80

2. A telephone-transmitter comprising a ring-shaped frame formed with an annular seat, a heavy disk made of rubber seated on the said seat, said disk being slightly dished on both faces, clamps secured to the frame, 85 and extending over the disk, said clamps being curved and having their ends only bearing on the disk, for securely holding the same to its seat, a bridge secured to the said frame, and extending over the said disk, and buttons, one of which is secured to the disk and the other to the said bridge, substantially as shown and described. 90

JAMES H. SPENCER.
